UNITED STATES PATENT OFFICE.

RUDOLPH F. HELLWEG, OF EL PASO, TEXAS.

BED.

1,350,155.

Specification of Letters Patent. Patented Aug. 17, 1920.

Application filed January 16, 1920. Serial No. 351,814.

To all whom it may concern:

Be it known that I, RUDOLPH F. HELLWEG, a citizen of the United States, and a resident of El Paso, in the county of El Paso, 5 and State of Texas, have invented a new and Improved Bed, of which the following is a full, clear, and exact description.

This invention relates to improvements in beds, an object of the invention being to 10 provide improved coupling means between the side rails of the bed and the head of the bed which will permit the rails to be located either in position to support a spring or to support slats and to facilitate this 15 double function, the side rails are of the ordinary angle iron form.

With these and other objects in view the invention consists in certain novel features of construction, and combinations and arrangements of parts as will be more fully hereinafter described and pointed out in the claims.

In the accompanying drawings—

Figure 1 is a perspective view illustrating 25 the side rail in one position;

Fig. 2 is a similar view showing the side rail in its reversed position;

Fig. 3 is a perspective view of the bed-post and frenching;

Fig. 4 is a perspective view of my improved coupling; and

Fig. 5 is a perspective view of the end of the rail.

1 represents a bedpost and 2 a block or 35 frenching fixed to the bedpost and adapted to support a rail 3. The rail 3 is of the angle iron type and it is the purpose of my invention to provide improved means for supporting the rail with its horizontal web 40 uppermost, as shown in Fig. 1, to support the ordinary spring or to support the rail with the horizontal web thereof at the base of the rail to receive the bed slats. The rail 3 has a block 4 fixed to its end which is of 45 substantially the same cross-sectional shape and area as the end of the frenching 2 and is adapted to lie flush against the same.

5 represents my improved coupling which is of metal and which consists of two coupling tongues 6 and 7 integral with each other and both of truncated conical form with the tongues 6 and 7 oppositely disposed so that the larger end of the tongue 6 and the smaller end of the tongue 7 are at 55 the same end of the coupling, as shown clearly in Fig. 4. The frenching 2 is made

in its outer end with a recess 8 and this recess 8 is of truncated conical form with the upper end thereof of greatest diameter and tapering or reducing in diameter to its 60 lower end. This recess 8 is adapted to receive the member 6 of the coupling 5.

The block 4 on the end of the rail 3 is provided with two recesses 9 and 10 located at right angles to each other and bisecting each other. These recesses 9 and 10 are of general truncated conical form and assuming the device to be in the position shown in Figs. 1 and 5, the recess 10 is of smallest diameter at its upper end and tapers or increases in diameter to its lower end. The other recess 9, when the parts are in this position, is horizontal and is of truncated conical form tapering from one end to the other. When the rail is in either of its operative positions, its recess 9 or 10 to receive the member 7 of the coupling 5, is largest at its lower end and tapers or reduces to its upper end so that it fits over the member 7 and is supported thereby. It will thus be 80 noted that the rail can be positioned as shown in Fig. 1 with the member 7 in the recess 10, or can be positioned as shown in Fig. 2 with the member 7 in the recess 9. It will therefore be noted that assuming the 85 rail to be in normal position, the recesses 9 and 10 are vertical and horizontal respectively, or vice versa, and the rail can be firmly and rigidly supported in either of its positions.

While I refer to the recesses as of truncated conical form, it is, of course, to be understood that the recesses extend to the ends of the frenching and the block 2 respectively, so that the coupling 5 can be accommodated 95 in said recesses as clearly shown.

It is also to be understood that while I have illustrated but one corner of the bed, the construction will be alike at all four corners.

Various slight changes may be made in the general form and arrangement of parts described without departing from the invention, and hence I do not limit myself to the precise details set forth but consider myself 105 at liberty to make such changes and alterations as fairly fall within the spirit and scope of the appended claims.

I claim:

1. In a bed corner, a frenching secured 110 to the corner post of the bed and having a tapering recess largest at its upper end and

tapering to its lower end, an angle rail, a block on the angle rail having a pair of recesses at right angles to each other, said recesses largest at one end and tapering to 5 their other ends, and a coupling comprising two coupling tongues integral with each other oppositely disposed and tapering from end to end, said coupling adapted to be positioned in the recess of the frenching 10 and in either of the recesses of the rail block.

2. In a bed corner, a frenching secured to the corner post of the bed and having a tapering recess largest at its upper end and 15 tapering to its lower end, an angle rail, a block on the angle rail having a pair of recesses at right angles to each other, said recesses largest at one end and tapering to their other ends, and a coupling comprising 20 two coupling tongues integral with each

other oppositely disposed and tapering from end to end, said coupling adapted to be positioned in the recess of the frenching and in either of the recesses of the rail block, said recesses and tongues of the locking 25 member of general truncated conical form.

3. In a bed corner, a frenching secured to the bedpost, and having a tapering recess in its end, an angle rail, a block on the angle rail, said block in its end having vertical and horizontal tapering recesses bisecting each other, and a coupling comprising two integral coupling tongues, said tongues tapering from end to end and reversely positioned, one of said tongues adapted to 30 be positioned in the recess of the frenching and the other of said tongues adapted to enter either of the recesses in the rail block.

RUDOLPH F. HELLWEG.
